WINCH HEAD DRIVE

Application filed August 8, 1927. Serial No. 211,302.

This invention relates in general to cranes, and more particularly to a winch construction or attachment especially designed and adapted for organization with a crane of the truck or trailer type.

In connection with the use or operation of cranes of this character it is convenient and desirable, and in fact, often essential, to have a power winch available. Various attempts have been made to organize a winch with this type of crane but they have been more or less unsatisfactory for a number of reasons.

Cranes of the character in question have a revolving platform mounted on a fixed sub-frame of the truck and the instrumentalities of the crane and the power means for operating the same are located on the revolving platform. The usual attempts that have been made to organize a winch construction with such a crane have involved the mounting of the winch head on the lower relatively stationary structure or sub-frame of the crane. In such constructions the winch heads were usually rotatable about a horizontal axis and this horizontal axis remains fixed in the sense that it did not swing with the revolving platform of the crane. This construction involves the very serious disadvantage of being capable of pulling only in the same direction in which the truck or trailer is standing, that is, fore and aft thereof, and when it is desired or is necessary to pull in a direction at right angles to that in which the truck is standing, then it becomes necessary to run the winch rope around a snatch-block, or the like. This consumes time, and thus delays the operation. Moreover, a suitable anchoring for the snatch-block is not always available. A still further disadvantage of such an arrangement resides in the rather heavy expense involved in equipping a crane with a winch construction of this character.

One of the principal objects of the present invention resides in the production of a simplified and comparatively inexpensive winch construction or attachment which is so organized with the crane as to be capable of pulling in any direction irrespective of the

position of the crane and without necessitating the use of snatch-blocks, or the like.

Another important object of the invention is to provide a machine of this character wherein the winch head is mounted at the axis of rotation of the revolving frame of the crane and is driven from the gearing which serves to swing or revolve the crane in either direction, whereby the winch head may be reversely rotated in any position of the revolving frame and may be utilized to exert a pull in any direction regardless of the position of the crane.

Other objects and advantages reside in certain novel features of the construction, arrangement and combination of parts which will be hereinafter more fully described and particularly pointed out in the appended claims, reference being had to the accompanying drawings forming a part of this specification, and in which:

Figure 1 is a fragmentary plan view of the revolving platform of a crane equipped with a winch in accordance with the present invention, parts being omitted for the sake of illustration; and

Figure 2 is a view in vertical section on line 2—2 of Figure 1, parts being omitted and parts being shown in section for the sake of simplicity in illustration.

Referring to the drawings, numeral 1 designates the usual combined swing-gear and roller path which is rigidly secured to the usual sub-frame (not shown) fastened to the truck or trailer in accordance with the usual practice. A revolving frame or platform 2 is supported for rotation on the combined swing-gear and roller path 1 in the usual manner.

For the dual purpose of constraining the revolving frame 2 to rotation about a fixed vertical axis and also for affording a mounting for the winch construction or attachment to be hereinafter more fully described, a hollow gudgeon pin 3 is interfitted with the frames 1 and 2, this pin 3 being suitable fitted in an opening 4 provided in the frame 1 and in a bushing 5 lining an opening 6 formed in the revolving frame 2. The lower end of the gudgeon pin 3 is flanged as at 7, the

flange 7 abutting the frame 1 under the action of a capstan nut construction 8 which coacts with the upper end of the gudgeon pin 3.

- 5 A power plant which may be an internal combustion engine 10 is supported on the revolving frame 2 and the engine shaft has a pinion 11 which meshes with a gear wheel 12 fixed to one end of a jack shaft 13. Oppositely disposed beveled gears 14 are mounted on the shaft 13 and are selectively clutched thereto by cone clutches 15. These beveled gears 14 constantly mesh with a beveled gear 16 fixed to the upper end of a vertical shaft 17 journaled in bearings provided thereon on the platform 2 and having a spur pinion 18 which meshes with an intermediate gear wheel 19 loosely mounted on a vertical swing shaft 20 rotatably supported in bearings provided on the revolving frame 2 and carrying a pinion 21 which constantly meshes with the fixed swing-gear 1. The gear 19, though rotatable on the shaft 20, may be clutched thereto by means of a sliding clutch member 22 splined on the shaft 20 and having teeth 23 adapted to interlock or intermesh with teeth 24^a formed on a cooperable clutch member 24 secured to the gear wheel 19. Suitable operating mechanism is provided for the various clutches, the operating mechanism for the clutch member 24 being designated at C.

35 By suitably manipulating the clutches 15 and sliding the clutch member 22 to intermesh the teeth 23 and 24^a, the revolving frame 2 may be swung in one direction or the other.

40 A vertical winch shaft 25 is rotatably fitted in the hollow gudgeon pin 3 and projects above the upper end of the gudgeon pin for a substantial distance. A winch head 26 is suitably fixed to the upper end of this winch shaft 25. Interposed between the winch head 26 and the upper end of the gudgeon pin 3 45 and fixed to the winch shaft 25, is a winch driving gear 27, this gear 27 constantly meshing with the intermediate gear 19 of the gearing which swings the revolving frame 2.

50 With this construction the winch head is located at the axis of rotation of the revolving frame and this relation of the winch head to the revolving frame makes it possible to utilize the winch head to pull in any direction regardless of the position of the crane and with 55 the revolving platform positioned as may be desirable. Of course, the revolving platform may be and frequently is rotated to present the best clearance in the direction of pull to prevent fouling of the winch rope. In this connection it is to be understood that forwardly of the winch head there is a wide clearance for the winch rope. Some lateral clearance is also available. The revolving platform may be swung in either direction 60 with facility but it is often inconvenient and

undesirable to move the entire crane. Movement of the entire crane is never necessary with applicant's construction. The swing-gear for revolving the frame is cut out or disconnected from the reversing clutch arrangement on the jack shaft by suitably manipulating the clutch member 22 and this is done when the winch head is to be rotated.

65 The winch head is rotated in either direction by selecting the proper clutch 15. It is 70 to be noted that in any position of the revolving platform the winch head may be rotated in either direction. The winch construction or attachment is extremely simple and involves, in connection with the novel swing-gear shown, merely the provision of a hollow gudgeon pin, the shaft 25, winch head 26, and gear 27, and the organization of these elements with the crane structure as hereinabove set out and as shown in the accompanying 75 drawings.

80 While the winch, when provided, is a permanent part of the crane equipment, it is an attachment in the sense that it is auxiliary or accessory equipment. Nevertheless, the 85 winch furthers the crane operations and in contributing to this single result, the winch coacts with the swing-gearing which rotates the revolving platform.

85 The invention claimed is:

1. A winch attachment for use with a crane having a stationary and a revolving frame and a hollow gudgeon pin constraining the revolving frame to rotation on the fixed frame, and comprising a shaft rotatably supported 100 in the hollow gudgeon pin, a winch head fixed to said shaft above the gudgeon pin, a gear wheel connected to said shaft between the winch and the adjacent end of the gudgeon pin, and means cooperable with the gear wheel 105 for rotating the said shaft and winch in either direction.

2. A winch attachment for use with a crane having a stationary and a revolving frame, a hollow gudgeon pin constraining the revolving frame to rotation on the fixed frame, and clutch controlled gearing for swinging the revolving frame in either direction, and comprising a shaft rotatably supported in the hollow gudgeon pin, a winch head fixed to the 115 upper end of said shaft, and a gear wheel fixed to the winch shaft between the winch head and the gudgeon pin and meshed with the clutch controlled gearing whereby the winch parts may be rotated in either direction 120 in any position of the revolving frame.

3. A winch attachment for use with a crane having a stationary and a revolving frame, means constraining the revolving frame to rotation on the fixed frame and clutch controlled gearing for rotating the revolving frame in either direction, and comprising a mounting supporting the winch for rotation about said means as an axis, a rotatable winch head on said mounting, and a gear wheel in 125 130

terconnected with the winch head so as to constrain the winch head to rotate therewith, said gear wheel intermeshing with said clutch controlled gearing and being driven thereby, whereby the winch head may be rotated in either direction in any position of the revolving frame.

In witness whereof, I hereto affix my signature.

ROLF LJUNGKULL.
